UNITED STATES PATENT OFFICE

FRANK SCHIFFL, OF HAMPSTEAD, LONDON, ENGLAND, ASSIGNOR TO RADIO CORPORATION OF AMERICA, A CORPORATION OF DELAWARE

REMOTE VOLUME CONTROL

Application filed March 6, 1931, Serial No. 520,757, and in Great Britain January 8, 1930.

The present invention relates to a method and apparatus for controlling the volume of sound reproduction as, for instance, in a talking moving picture performance. More particularly, it relates to an apparatus for control of the volume by an observer seated in the audience.

Hitherto, it has been usual to control the volume of the sound reproduced in a talking movie production from the projection booth. The projection booths are usually enclosed, and it is impractical for the projectionist to accurately determine the effectiveness of the volume being emitted by the loudspeaking equipment. Therefore, it is usual to post an observer in the audience, which observer acting in conjunction with the projectionist by means of suitable signals such as electric light circuits or annunciators, indirectly controls the volume. Such an arrangement has a considerable disadvantage in that the projectionist must when signalled, leave his post of observation and turn to the amplifier control panel to make the required adjustment of the volume control in accordance with the signals thus transmitted to him. Not only does this system require that the projecting part of the apparatus be left unattended, but due not only to the personal equation but to the inherent time lag due to shifting attention from the projecting to the sound equipment, the response to the observer's signals is often not sufficiently rapid to be effective, and indeed frequently produces ludicrous results.

The object of the present invention is to obviate these disadvantages.

A more particular object of this invention is to produce an apparatus to enable the volume to be directly controlled by the observer stationed in the audience.

A further object of this invention is to produce a system which shall contribute to a more finished talking movie effect by a proper volume control arrangement.

These and other objects of this invention will become apparent from the following specification taken in connection with the appended drawings.

In accomplishing the objects of my invention, the spindle of the potentiometer used

to control the volume of the sound reproducing amplifier is so connected that it is adapted to be rotated optionally in either direction by means of an electrically operated ratchet and pawl, or similar mechanism, the circuits for controlling which are adapted to be opened and closed at will by the observer.

Preferably, the mechanism comprises a pair of solenoids, the circuits of which are controlled by a pair of electric switches or a double-throw electric switch installed at the observation point. The cores of the solenoids are adapted to actuate the pivotally mounted pawls, which in turn are adapted to co-act with the surface of a ratchet so disposed on a shaft as to control the turning of the potentiometer controlling the volume of the loudspeakers.

Having thus briefly described my invention, attention is invited to the accompanying figures in which;

Fig. 1 is a general view of the apparatus comprising my invention;

Fig. 2 is a projection showing the flexible connection between the potentiometer shaft and the actuating ratchet, and;

Fig. 3 is a cross-section of one of the solenoids of my invention, showing in detail one of the pawls and its actuating mechanism.

Attention is particularly invited to the figures illustrating one form of my invention in which like parts are designated by like reference characters.

The spindle 11 of a rheostat potentiometer, generally indicated at 13, connected in the amplifier circuit of the sound reproducing apparatus, is connected by means of the flexible coupling, (Fig. 2) comprising a pin 15 mounted on a disc 17, which in turn is mounted on the ratchet spindle *a* of the control mechanism, coacting with a fork 21 secured to the said shaft 11. The control mechanism comprises a pair of solenoids *e*—*e* arranged to be actuated by suitable switches, as mentioned above, which, per se, constitutes no part of the present invention, and a ratchet and pawl mechanism for driving the said spindle *a*. On the spindle *a* is mounted a ratchet wheel *b*, the periphery of which is formed with V-shaped teeth as shown. The spindle is car-

ried in bearing brackets *c* mounted on base plate *d* beneath which are mounted the solenoids *e*—*e*, on opposite sides of the center of the ratchet wheel *b*.

5 Referring now more particularly to Fig. 3, mounted in the core of the solenoid *e* is an armature *f* mounted on the armature rod *g*. The rod *g* extends through the base plate *d* and has on its upper end a head *h* which is 10 formed with inclined faces *j* and *k*. The head *h* is slideable in a guide tube *m* mounted on the upper side of the base plate *d*. Also slideably mounted in the guide tube *m*, above the head *h*, is a bifurcated block *n*, the lower end 15 of which has surfaces *o* and *p* corresponding in angle to the surfaces *j* and *k* respectively of the head *h*. Between the limbs of the bifurcated block is pivoted a pawl *q* formed with a tooth *r* and faces *s* and *t* corresponding with 20 faces *j* and *k*, and *o* and *p* respectively.

The tooth *r* of the pawl *q* is arranged so that when it is in the position shown, it will clear the teeth of the ratchet wheel *b*. However, when the block *n* is moved upward by 25 means of the head *h*, the surfaces *j* and *k* of the head *h* will coact respectively with the faces *s* and *t* of the pawl *q*, and will rotate the pawl so that the tooth *r* will engage one of the V-shaped teeth on the ratchet *b*, as will 30 be described more in detail hereinafter.

The solenoids *e*—*e* are connected through suitable conductors *u* and *v* with a switch 30 conveniently located in the hall or auditorium where the reproduction is taking place. The 35 arrangement is such that when a switch 30 is closed in one direction, one of the solenoids *e*—*e* becomes energized, and its armature *f* is raised. The first part of the upward movement of the armature *f* raises the head 40 *h* until its faces *j* and *k* coact respectively with the corresponding faces *s* and *t* of the pawl *q*, and serve to tilt the pawl out so that the tooth *r* of the said pawl will be brought under a tooth of the ratchet wheel *b*.

45 Further movement upward of the armature *f* will raise the block *n*, and the tooth *r* will cause the ratchet to rotate until the upward movement of the block *n* is limited by means of the adjustable stop *w* at the top of 50 the tube *m*. When the circuit of the solenoid is broken, the armature *f*, rod *g*, head *h*, block *n*, and pawl *q* will return to their normal positions leaving the ratchet wheel in the angular position to which it has been moved.

55 Hence, by operating one or the other of a pair of switches, the ratchet wheel *b* and the spindle of the potentiometer are turned in one direction or the other to increase or decrease the volume of reproduction, it being understood that if greater variation of volume is required than results from the closing of the solenoid circuit once, the potentiometer spindle may be moved step by step to the required extent by successive closings of the circuit.

60 In this manner, the volume of the sound

reproduction is directly under the control of the observer, permitting the operator to attend to the projector portion of the apparatus.

It is obvious that instead of the tooth 70 ratchet wheel shown, a friction pad may be provided upon the pawl, and the ratchet wheel may have a plain, a circumferentially grooved, or other suitable periphery.

Having thus described one embodiment of 75 my invention, it is to be understood that various modifications may be made therein, and that I am therefore not to be limited to the specific embodiment shown and described for the purpose of illustration only, but by 80 the actual scope of my invention as set forth and determined in the appended claim.

I claim:

In talking motion picture apparatus having picture projecting means, phonographic 85 apparatus and an amplifier within a projection booth adjacent an auditorium, and having a picture projecting screen and sound reproducing means visible and audible from said auditorium, means for controlling the 90 volume of sound reproduction by controlling the amplifier from a point within the said auditorium comprising a variable resistance element constituting a portion of the said amplifier, means for rotating the control means 95 of the said resistance element comprising a pair of solenoids, a pair of cores for the said solenoids, a pawl in cooperative relation with each of said cores and a ratchet wheel on the rotatable control member of the said resistance adapted to be selectively rotated in either direction by the operation of one or the other of said pawls; and a pair of switches 100 at the said point in the said auditorium connected to and adapted to operate the said solenoids, whereby an observer in the said auditorium may rotate the said control member in either direction to control the volume of sound produced by the said sound reproducer.
